Ames & Sibold. ATTORNEYS

UNITED STATES PATENT OFFICE

WILLIS STUTSON, OF WINNETKA, ILLINOIS

DOVETAIL

Application filed March 27, 1931. Serial No. 525,799.

My invention relates to a dovetail construction.

One of the objects of my invention is to provide an improved dovetail construction.

5 One of the objects of my invention is to provide an improved wear-resisting self-lubricating easy-operating construction.

Further objects will appear from the description and claim.

10 In the drawings, in which an embodiment of my invention is shown,

Figure 1 is a horizontal sectional view on the line 1—1 of Fig. 2, showing the swinging edge of the door with the projecting construction mounted thereon and the adjacent portion of the body construction with the receiving portion mounted thereon;

Fig. 2 is a section on the line 2—2 of Fig. 1;

Fig. 3 is a section on the line 3—3 of Fig. 1;

20 Fig. 4 is a section on the line 4—4 of Fig. 1, and

Fig. 5 is a section on the line 5—5 of Fig. 1.

Referring to the drawings in detail, the construction shown comprises a receiving member in the form of a convoluted leaf spring 1 secured inside the door post 2 as by spot-welding or the like, and a projecting member comprising a sheet metal stamping 3 and a block 4 of thermo-plastic self-lubricating wear-resisting material mounted in a pocket 5 in the sheet metal member and having upper and lower wear portions 6 projecting through corresponding openings in the pocket into position to engage the pocket formed in the spring-receiving member 1. In order to facilitate opening the door and easy entrance of the projecting member, it is made of tapered formation, the spring pocket on the receiving member being correspondingly tapered, as shown in Figs. 2 and 3. The sheet metal pocket member may be provided with upper and lower flanges 7 through which securing screws extend into the door, as shown in Fig. 1. The block of thermoplastic material may be inserted into the pocket in the sheet metal member through the space provided between the upper and lower flanges, as may be seen from Fig. 5.

The thermoplastic material used has great 50 wear-resisting qualities and also self-lubri-

cating properties, which avoid the necessity for putting oil on the operating parts. The receiving spring may be secured to the post by spot-welding, as indicated at 8.

Further modifications will be apparent to those skilled in the art and I desire, therefore, to be limited only by the prior art and the scope of the appended claim.

Having thus described my invention what I claim and desire to secure by Letters Patent is:

A dovetail construction comprising a projecting member for cooperation with a receiving member, said projecting member construction comprising a block of thermoplastic material having lubricating and wear-resisting properties, a metal housing and holder for said block comprising a pocket portion in which the block is seated, and a securing flange portion, said pocket having an opening through which said block projects for engagement with the receiving member.

In witness whereof, I have hereunto subscribed my name.

WILLIS STUTSON.
